UNITED STATES PATENT OFFICE.

EZECHIEL WEINTRAUB, OF SCHENECTADY, NEW YORK, ASSIGNOR TO GENERAL ELECTRIC COMPANY, A CORPORATION OF NEW YORK.

ELECTRIC LAMP.

1,086,103.

Specification of Letters Patent.

Patented Feb. 3, 1914.

Application filed February 26, 1902. Serial No. 95,662.

To all whom it may concern:

Be it known that I, EZECHIEL WEINTRAUB, a subject of the Czar of Russia, residing at Schenectady, county of Schenectady, State of New York, have invented certain new and useful Improvements in Electric Lamps, of which the following is a specification.

The invention which I have hereinafter described and claimed relates to methods of producing light by electricity and to certain improvements in electric lamps of that type in which electrical energy is converted into light through the medium of vaporous or gaseous matter maintained in a luminescent condition by the electric current. In an application filed concurrently herewith, I have described and have claimed broadly certain features of invention whereby a lamp of this character may be started into operation, together with other correlated features unnecessary here to mention. In the present application I propose to disclose certain arrangements for securing automatic operation of the lamp, the novel features of which arrangements will be pointed out in the following specification, in which—

Figure 1 represents one embodiment of my invention, Fig. 2 a modified detail and Fig. 3 a different form of the invention.

I will premise my description of these detailed arrangements by stating that in lamps of the general character mentioned, various difficulties and disadvantages have heretofore been attendant upon the means employed for starting the arc. The usual method of starting, of which of course there are various modifications, is to impress upon the terminals of the lamp, for a certain period or periods, a high electromotive force, many times greater in value than the normal electromotive force at which the lamp is intended to operate. This starting electromotive force apparently operates to break down the high initial resistance between the electrodes of the lamp whereupon the lamp starts.

My present invention, among other valuable features, provides means operating automatically upon turning on the current whereby a lamp of the type mentioned will start into operation by the utilization of electromotive force no greater than that impressed upon the lamp circuit by the supply mains. The starting is performed by producing locally within the lamp ionized vapor

which, by the migration of its ions or by some other operation the nature of which is not known with certainty, permits the application of the normal voltage to the terminals of the lamp to start the lamp into operation. 60 After the lamp has been started, the supplemental or auxiliary source of ionized vapor may be cut out of circuit and to perform this function as well as to initiate automatically the production of ionized vapor, 65 I may make use of the arrangements shown in the drawings above referred to.

Referring to Fig. 1, the lamp will be seen to consist of a main tube 1 of indefinite length, indicated by the dotted lines 2. At 70 either end of the lamp are electrodes, the lower electrode consisting in the present instance of a body of mercury filling a narrow downward extension 4 of the lamp and also a small portion of the main body of the 75 tube as indicated. In the upper portion of the tube is located the other main electrode, consisting of a somewhat bell-shaped body 7 of suitable material as metal or graphite. This electrode communicates through a 80 sealed-in wire 8 with a body of mercury 9 contained in an exhausted chamber 10 out of which extends a wire 11 sealed through the walls of the chamber, the projecting end of the wire forming one of the external terminals of the lamp. The lamp itself is exhausted to as high a degree of vacuum as possible, the process of preparing and evacuating a lamp being set forth in the application above referred to, which process however forms no portion of the invention claimed herein. That the vacuum thus produced may be maintained in as perfect a condition as possible, the electrode 7 is connected with the exterior terminal 11 through 85 the evacuated chamber 10 as a precautionary measure. 90

Communicating with the main tube 1 is a chamber 12 of somewhat cylindrical shape, the lower end of which is contracted as at 13 100 and filled with mercury up to the level sufficient to cover the connecting neck 14 of the tube and thereby afford electrical connection between the body of mercury 3 in the main tube and the mercury in the communicating chamber 12. Within the chamber 12 is mounted a body of magnetic material consisting in this instance of a rod or a bunch of iron wires 15 contained within a glass tube 16 from which the air has been ex- 110

hausted. Located within proper relation to this iron rod or bunch of wires is a solenoid 16' which, when energized, is adapted to withdraw the tube containing the iron core 5 to a greater or less extent out of the mercury in which it is partially immersed. In order that the movements of this tube within its inclosing chamber shall not endanger the walls of the chamber, the tube is provided 10 at its ends with springs 17-18 adapted to serve as buffers. In order to render the displacement of the tube 16 as great as possible, the spaces between the iron and the tube may be filled with mercury.

15 Current may be supplied to the lamp from a suitable source of current, and connection therewith may be made by mains indicated at 19 and 20. One of these mains, as the main 19, may be connected to the lower terminal 5 of the lamp, while the other main 20 through a switch 21 may be connected to the upper terminal 11 of the lamp. The lead extending from the switch 21 is connected through the fixed contacts 22 and 23 of a 25 cut-out apparatus 24 to a sealed-in terminal 25 of the lamp which terminal communicates with the mercury in the tubular chamber 12 and forms an auxiliary or supplemental electrode for the lamp, the terminals 30 5 and 11 acting as the main terminals during operation.

In series with the circuit between the main 20 and the auxiliary terminal 25 is the solenoid 16' and a current limiting resistance 35 26. The main terminal 11 of the lamp is connected to the same supply lead as the auxiliary terminal 25 and the conductor forming this connection includes therein a resistance 27 and the solenoid or magnet 28 40 of a cut-out device 24, which magnet acts upon a core 29 carrying a bridging contact adapted when no current flows in the solenoid or magnet to bridge over the fixed contacts 22 and 23, and to break this bridging 45 connection when current does flow in the magnet or solenoid.

In the operation of starting the lamp, the switch 21 may be closed, thereby first causing current to pass through the solenoid 16' 50 and through the body of mercury in the lamp to the other terminal of the source of current. The resulting current, which is limited in value by the resistance 26, causes the tube 16 to be lifted out of the mercury 55 by the action of the solenoid 16', thereby lowering the level of the mercury and opening the circuit through the same at or about the point 30. The resulting arc or discharge which takes place causes a liberation 60 of mercury ions which operate to set up the flow of current through the main tube between the main electrodes of the lamp. As soon as this current commences to flow, the cut-out device 24 operates and interrupts the 65 branch current initially flowing into the

lamp at the terminal 25 and maintains the same out of circuit until the main current is for any reason interrupted, whereupon the operation above described is repeated.

Instead of inclosing the iron constituting 70 the armature or core of the solenoid 16' in a glass tube, it may be arranged, as shown in Fig. 2, to be movable longitudinally of a guiding tube 31 located as shown within the chamber 12. Both ends of the armature may 75 be provided with buffer springs indicated at 32 and 33. The guiding tube 31 has a small opening 34 communicating, above the surface of the mercury, with the chamber 12 whereby its contents may be evacuated when 80 the evacuation of the main tube takes place.

In Fig. 3 is shown a different arrangement for securing an automatic starting of the lamp. In this case the lower main electrode consists as before of a body of mercury 34 85 while the supplemental electrode likewise consists of a body of mercury 35. The level of the mercury of these two electrodes is such however that the mercury does not quite bridge over the space between them 90 but leaves a gap as at 36. Carried by the tube in any suitable manner is a body of magnetic material 37 in coöperative relation to which is mounted a solenoid 38. This solenoid is connected in a circuit between 95 one of the supply mains 20 and the supplemental electrode 35. A resistance 39 connects the electrode 35 with the other supply main 19. When the main switch 40 is closed, the solenoid 38 attracts its core 37 carried 100 by the lamp which may be suspended by the ring 41 or otherwise so that it may swing. With proper adjustment of parts the motion produced by the solenoid 38 causes a momentary flow of the mercury between the 105 electrodes 34 and 35 so as to connect the same, which flow, as it recedes, opens the circuit between the electrodes and springs an arc, setting free the ionized mercury vapor which operates to start up the main tube. 110 As soon as the main current commences to flow, a cut-out 42, arranged and connected like the cut-out 24 in Fig. 1, opens the circuit of the solenoid 38 and renders the same inactive until the current through the lamp 115 ceases to flow, whereupon if the switch 40 still be closed to the mains, the operation above described is repeated.

In the lamps which I have above described, the electrodes at the upper end of each lamp, 120 as represented at 7 in Fig. 1 and at 43 in Fig. 3, may be made of any one of a number of different materials such as iron or graphite. Of these I prefer the latter since it does not readily occlude gases, or, if it does, 125 then it readily gives them up; nor does it, when heated, undergo chemical change such as to generate gases, thereby impairing the vacuum of the lamp.

Although the automatic cut-out to which 130

I have heretofore referred may be used or not, as desired, to interrupt the supplemental or auxiliary circuit, it need not always, when used in this connection, be arranged to 5 interrupt the circuit but may, under certain conditions, be employed to vary the resistance of this circuit by opening or closing a short circuit about a portion or all of the resistance in this supplemental circuit; and 10 further it may, if desired, be adjusted so as to perform these functions at any selected current value. Thus if it is desired to run current in the main tube at a low value, for example, the cut-out may be arranged so as 15 to short-circuit a portion of the resistance in the supplemental circuit, thereby increasing the current flow therein and so maintaining stable operation of the lamp at the selected low current value. Or it may be adjusted 20 to reduce the supplemental circuit current when the main arc starts, as when the main arc is in operation the supplemental arc will run on lower current.

What I claim as new and desire to secure 25 by Letters Patent of the United States, is—

1. The combination in a vapor electric apparatus containing a conducting liquid, of a main circuit terminal in contact with said liquid, a supplemental starting circuit terminal engaging said liquid, and automatic means responsive to an application of potential to said apparatus for separating said conducting liquid into two portions to form a main electrode and a starting electrode.

2. The combination with supply mains, of a vapor electric apparatus connected thereto and comprising a tube, a pair of main electrodes mounted in said tube and having an unobstructed passage between them, said electrodes being at no time subjected to an electromotive force higher than that of said supply mains, a supplemental electrode, and automatic means for causing current to flow between said supplemental electrode and one of said main electrodes to produce a starting arc in said tube.

3. The combination with supply mains, of a vapor electric apparatus connected thereto and comprising a tube, main electrodes located therein and having a straight and unobstructed passage between them, said electrodes being at no time subjected to electromotive force higher than that of said supply mains, a supplemental electrode, and electrically controlled means responsive to the electromotive force of said supply mains for producing a starting arc in said tube.

4. The combination with supply mains, of a vapor electric apparatus comprising a tube, main electrodes therein having a straight and unobstructed passage between them, a supplemental electrode arranged so as to make and break contact with one of said main electrodes, and connections between said electrodes and said supply mains where-

by the electromotive force impressed upon said electrodes is at no time in excess of that of the supply mains.

5. The combination of an exhausted envelop, a cathode therefor adapted to emit 70 vapor, and a co-operating anode of graphite.

6. The combination with a straight tubular exhausted envelop, main electrodes at opposite ends of said envelop, a side chamber opening out of said envelop in alignment 75 with one of said main electrodes and out of alignment with the other, a supplemental electrode in said side chamber, and means operating by the agency of said supplemental electrode for momentarily causing a localized production of ionized vapor in said envelop.

7. The combination with an exhausted envelop, main electrodes therefor, a supplemental mercury electrode adjacent one of said 85 main electrodes, and electrically controlled means for varying the level of said mercury electrode to make and break contact between said supplemental electrode and the adjacent main electrode.

8. In a gas or vapor electric apparatus of the character described, the combination of a liquid negative electrode, a supplemental positive electrode mounted adjacent the edge 95 of said negative electrode, a working positive electrode mounted perpendicularly above the surface of said negative electrode and directly exposed thereto, means for bringing said supplemental positive electrode into contact with the negative electrode, means for automatically separating said electrodes when current flows through the apparatus to draw an arc substantially parallel to the surface of said negative electrode and simultaneously causing current to 100 pass between the negative electrode and said working positive electrode.

9. A mercury vapor arc lamp comprising a container for mercury, electrodes or contacts in said container normally connected 110 by the mercury in said container, means to separate the mercury between said electrodes or contacts to start the lamp and a resistance controlling the flow of current through the lamp, substantially as set forth.

10. In a gas or vapor apparatus of the character described, the combination of a liquid negative electrode, a liquid positive electrode adjoining said negative electrode, a main positive electrode mounted directly 120 above said negative electrode in a position to be directly exposed thereto, means for causing said liquid electrodes to coalesce and to separate, and means brought into operation by the separation of said liquid electrodes 125 for automatically substituting the other positive electrode for the liquid positive electrode.

11. In a vapor electric apparatus, the combination of an exhausted envelop, main 130

electrodes therefor one at least of which is vaporizable, and a magnetically controlled supplemental liquid electrode brought into and out of contact with one of said main electrodes by variations in level.

12. The combination of an exhausted envelop, a main anode therein, a vaporizable liquid cathode, a supplemental liquid anode mounted adjacent said cathode to make and 10 break contact therewith, and magnetic means for varying the level of said liquid electrode to control the relation thereof.

13. The combination of an exhausted envelop, a main anode therein, a mercury cathode consisting of a body of mercury sepa- 15

rable into two distinct parts, a positive terminal connected to one of said parts, a displacing device for controlling the level of said body of mercury, and electro-magnetic means for withdrawing said displacing device from said body of mercury to separate said body and thereby form an arc between the mercury connected to said positive terminal and the mercury cathode. 20

In witness whereof I have hereunto set 25
my hand this 24th day of February, 1902.

EZECHIEL WEINTRAUB.
